UNITED STATES PATENT OFFICE

FRANCIS J. CARNELLI, OF NEW YORK, N. Y.

WRENCH

Application filed April 30, 1930. Serial No. 448,640.

This invention relates to wrenches particularly adapted for turning pipes and the like, but obviously can be used for engaging nuts or bolts; and is of the type known in the trade as a Stillson wrench.

The main object of the invention is to provide improvements in the means for adjusting and holding the movable jaw member.

10 A further object of the invention is to provide a wrench of this character, in which the threaded shank that carries the movable jaw is advanced by turning a nut, with improved means for retaining the nut in the transverse 15 socket on removal of the jaw and shank.

Another object of the invention is to provide an improved form of spring and nut, in which both the nut and the spring will be retained in the socket bore on removal of the movable jaw member.

In the accompanying drawings showing one embodiment of my invention.

Figure 1 is a side elevation.

Fig. 2 is a plan view.

25 Fig. 3 is a vertical section at one end.

Fig. 4 is a perspective view of the handle jaw portion.

Fig. 5 shows the nut detached.

Fig. 6 shows the spring detached.

30 As shown in the drawings the handle 2 is provided with the usual end jaw face 3, that is slightly inclined; and is further provided with a lateral extension 4, at the jaw end. This extension has a bore 5 extending in the direction of the handle axis, and is somewhat oblong in section. The other jaw member comprises a flattened shank 6 that has screw threads on two of its sides, to receive a nut 7 that turns thereon; and at one end of the 40 shank is a jaw 8. The shank 6 is slidable in the extension bore 5 that will bring the jaw 8 opposite the other jaw 3 to approach and recede as the shank slides in the extension bore.

45 The extension 4 is further provided with a cross bore 9, that intersects the shank bore 5, and is made wider to provide shoulders at 10 and 11 towards the jaw end of the shank; and is also provided with shoulders 12 and 13 at the opposite end of the bore. This

cross bore will permit insertion of the nut 7, whose aperture will be brought to register with the bore 5, and then the shank 6 is inserted in the outer end of the bore 5 to engage and screw into the nut 7, that is then turned 55 to have the shank pass through the bore 5 until the jaw 8 is brought opposite the jaw 3; and it will be seen that the flat faces of the shank prevents its turning in the flattened bore 5. It will be readily understood that 60 the nut 7 will have one end face as 14, engage the shoulders 10 and 11. The diameter of the adjusting nut is such that its side walls 16 are free from the opposite walls 17 and 18, so that the nut and shank 6 can swing in the 65 plane of the handle and extension, and the shank jaw has the usual movement towards and from the other jaw on turning of the nut 7.

It will be understood that the usual pressure between the two jaws will tend to move the shank outward, and this will be limited by the engagement of the curved face 14 of the nut with the shoulders 10 and 11 of the extension bore. This engaging face 14 of the 75 nut is preferably made curved or spherical, to facilitate its swinging on these engaging faces.

Means are further provided to retain the nut 7 against these shoulders 10 and 11, and 80 which will also tend to swing the shank to cause approach of the opposed jaws. A coil spring 19 is provided between the rear face of the nut 7 and the rear shoulders 12 and 13, the nut 7 being preferably provided with a 85 shoulder 15 at its rear end to receive the spring 19. The spring may have its end 20 engage the outer edge of the rear wall 12 on one side, while the other extremity 21 of the spring passes rearward and engages the outer 90 opposite edge of the rear wall 13 as shown. It will be seen that this spring will press the nut forward tending to hold its curved face 14 against the shoulders 10 and 11. This rear wall at 12 and 13 of the extension 95 is shown inclined rearwardly toward the handle, and with the opposite end, convolutions of the spring being made parallel, it will tend to tilt the threaded shank 6, and move the jaw 8 inwardly or toward the han- 100

dle jaw 3. It will be further seen that the nut is engaged at its rear shoulder by the coil spring, so that when the shank 6 is moved entirely forward on turning the nut, the nut 5 will still be held inside of the extension, and not fall out; but at the same time can be easily inserted and removed on compression of the coil spring.

It will be understood that the usual pin on 10 which the frame is carried is omitted and its function is performed by the spherical end of the nut engaging an inner wall or shoulders of the jaw member, or handle element of the wrench. Working with this is the coil 15 spring removably inserted with the nut, which puts pressure on the outer edge of the nut and serves to place the initial tension on the movable jaw, that renders it more efficient in getting that initial hold of the 20 pipe which permits the handle to turn on its fulcrum, and supply sufficient pressure on the pipe so that it can be turned. This spring has two other functions also; if the movable jaw is turned out of the nut, it holds 25 the nut in the wrench against accidental removal; intentional removal is easily possible by pressing down and then ejecting sidewise. The second function of the spring is to keep 30 continual pressure on the nut holding it in its seat, that reduces the amount of play in the wrench itself, and will reduce the amount of handle movement in taking the next grip. With wear on the threads, both internal and 35 external, the nut tends to become loose, so that with ordinary pipe wrench it is sometimes necessary to hold the nut with one hand while moving the wrench, so that the opening adjustment of the wrench will not change between the time of setting the wrench open- 40 ing and applying it to the pipe. The invention essentially comprises a four part wrench having true wrench characteristics, includ- 45 ing adjustability for pipe sizes, full bearing at the nut, variable angle at the movable jaw, initial pressure on the jaws, spring pressure 50 on the nut to keep it taken up at all times, and to keep nut adjustment where set irrespective of nut wear, detachable retainer for the nut, with cam pressure on the pipe to set the jaws.

It is to be understood, that while I have described in detail one practical embodiment of my invention, it can be altered in the form, 55 relation arrangement and construction of the parts, and modifications can be made within the perview of the invention, without departing from the scope of the claims, and without departing from the spirit and import of the invention.

60 What I claim is:—

1. In a wrench, a handle bar, a fixed jaw at the forward end of the handle bar, an extension on the back of the forward portion of the handle bar and provided with 65 a slot extending transversely through the ex-

tension to form spaced lugs, said slot having its forward wall arranged to form a nut seat, said spaced lugs having aligned slots therein, a threaded shank slideable and tilt- 70 able in the slots of said lugs, a jaw on the forward end of said shank, a nut rotatable on the shank in said first slot and bearing against the forward wall of said first slot, and a coiled spring surrounding the shank and bearing at one end on the nut and at its 75 other end on the rear wall of the first slot said rear wall being inclined and arranged to tilt the forward end of the shank toward the fixed jaw.

2. In a wrench, a handle bar, a fixed jaw 80 at the forward end of the handle bar, an extension on the back of the forward portion of the handle bar and provided with a slot extending transversely through the extension to form spaced lugs, said slot having its forward wall arranged to form a nut seat, and its rear wall inclined forwardly from the handle bar outwardly, said spaced lugs having aligned slots therein, a threaded shank slide- 85 able and tilttable in the slots of said lugs, 90 a jaw on the forward end of said shank, a nut rotatable on the shank in said first slot and bearing against the forward wall of said first slot, and a coiled spring surrounding the shank and bearing at one end of the nut 95 and at its other end on the rear wall of the first slot and arranged to tilt the forward end of the shank toward the fixed jaw.

3. In a wrench, a handle bar, a fixed jaw at the forward end of the handle bar, an extension on the back of the forward portion of the handle bar and provided with a slot extending transversely through the extension to form spaced lugs, said slot having its forward wall arranged to form a nut seat, 100 said spaced lugs having aligned slots therein, a threaded shank slideable and tilttable in the slots of said lugs, a jaw on the forward end of said shank, a nut rotatable in the shank in said first slot and bearing against the forward wall of said first slot, and a coiled spring surrounding the shank and bearing at one end on the nut and at its other end on the rear wall of the first slot said rear wall 105 being inclined and arranged to tilt the forward end of the shank toward the fixed jaw, said nut having an annular shoulder at its rear end forming a seat for the forward end of said spring.

4. In a wrench, a handle bar, a fixed jaw 115 at the forward end of the handle bar, an extension on the back of the forward portion of the handle bar and provided with a slot extending transversely through the extension to form spaced lugs, said slot having its forward wall arranged to form a nut seat and its rear wall inclined forwardly from the handle bar outwardly, said spaced lugs having aligned slots therein, a threaded shank slideable and tilttable in the slots of said lugs, 125 130

5 a jaw on the forward end of said shank, a nut rotatable on the shank in said first slot and bearing against the forward wall of said first slot, and a coiled spring surrounding the shank and bearing at one end of the nut and at its other end on the rear wall of the first slot and arranged to tilt the forward end of the shank toward the fixed jaw, said nut having an annular shoulder at its rear end 10 forming a seat for the forward end of said spring.

15 5. In a wrench, a handle bar, a fixed jaw at the forward end of the handle bar, an extension on the back of the forward portion of the handle bar and provided with a slot extending transversely through the extension to form spaced lugs, said slot having its forward wall arranged to form a nut seat, said spaced lugs having aligned slots there- 20 in, a threaded shank slidable and tilttable in the slots of said lugs, a jaw on the forward end of said shank, a nut rotatable in the shank in said first slot and bearing against the forward wall of said first slot, and a coiled spring surrounding the shank and bearing at one end on the nut and at its other end on the rear wall of the first slot said rear wall being inclined and arranged to tilt the forward end of the shank to- 25 ward the fixed jaw, said nut having an annular shoulder at its rear end forming a seat for the forward end of said spring, said nut further having a segmento-spherical forward face engaging the forward wall of the first slot.

35 6. In a wrench, a handle bar, a fixed jaw at the forward end of the handle bar, an extension on the back of the forward portion of the handle bar and provided with a slot extending transversely through the extension to form spaced lugs, said slot having its forward wall arranged to form a nut seat and its rear wall inclined forwardly from the handle bar outwardly, said spaced lugs having aligned slots therein, a threaded shank slidable and tilttable in the slots of said lugs, a jaw on the forward end of said shank, a nut rotatable on the shank in said first slot and bearing against the forward wall of said first slot, and a coiled spring surrounding the shank and bearing at one end of the nut and at its other end on the rear wall of the first slot and arranged to tilt the forward end of the shank toward the fixed jaw, said nut having an annular shoulder at its rear end forming a seat for the forward end of said spring, said nut further having a segmento-spherical forward face engaging the forward wall of the first slot, said spring having its ends arranged to bear against opposite sides of the extension and thereby prevent rotation of the spring on the shank.

45 7. In a wrench, a handle bar, a fixed jaw at the forward end of the handle bar, an extension on the back of the forward portion of the handle bar and provided with a slot extending transversely through the extension to form spaced lugs, said slot having its forward

50 wall arranged to form a nut seat, said spaced lugs having aligned slots therein, a threaded shank slidable and tilttable in the slots of said lugs, a jaw on the forward end of said shank, a nut rotatable in the shank in said first slot and bearing against the forward wall of said first slot, a coiled spring surrounding the shank and bearing at one end on the nut and at its other end on the rear wall of the first slot said rear wall being inclined and arranged to tilt the forward end of the shank toward the fixed jaw, said nut having an annular shoulder at its rear end forming a seat for the forward end of said spring, said nut further having a segmento-spherical forward face engaging the forward wall of the first slot, and means to prevent rotation of the spring on the shank.

55 8. In a wrench, a handle bar, a fixed jaw at the forward end of the handle bar, an extension on the back of the forward portion of the handle bar and provided with a slot extending transversely through the extension to form spaced lugs, said slot having its forward wall arranged to form a nut seat and its rear wall inclined forwardly from the handle bar outwardly, said spaced lugs having aligned slots therein, a threaded shank slidable and tilttable in the slots of said lugs, a jaw on the forward end of said shank, a nut rotatable on the shank in said first slot and bearing against the forward wall of said first slot, and a coiled spring surrounding the shank and bearing at one end of the nut and at its other end on the rear wall of the first slot and arranged to tilt the forward end of the shank toward the fixed jaw, said nut having an annular shoulder at its rear end forming a seat for the forward end of said spring, said nut further having a segmento-spherical forward face engaging the forward wall of the first slot, said spring having its ends arranged to bear against opposite sides of the extension and thereby prevent rotation of the spring on the shank.

60 Signed at New York City, N. Y., on April 28, 1930.
